TARGET ASSEMBLY WITH REMOVABLE TARGET
CHUTES OF VARYING HEIGHT

Allendale, N.J. 07401
Filed July 10, 1964, Ser. No. 381,721
5 Claims. (Cl. 273—95)

This invention relates to an amusement device, and, more particularly, to a game of skill for one or more players employing a multi-compartmented receptacle into which a ball is thrown or bounced.

In accordance with this invention, a target is provided comprising a plurality of chutes of varying heights which are sized to loosely receive a ball. Each of the chutes is assigned a point value determined on the basis of the relative difficulty of bouncing or throwing a ball therein. The game is particularly appealing since the chutes are individually removable and can be rearranged to lend variety to the game and to alter the ease of scoring in accordance with the skill of the players. This feature also facilitates recovery of balls which have successfully landed in one of the chutes.

It is, therefore, an object of the present invention to provide a game employing a ball-receiving receptacle which includes a plurality of chutes of varying heights.

Another object is to provide a ball-receiving receptacle which includes a plurality of individually removable chutes.

A further object is to provide a multi-compartmented base which supports a plurality of vertically aligned chutes of varying height that can be rearranged in accordance with the desires of the players.

Other objects will appear from the specification and drawings, in which:

FIGURE 1 is a perspective view illustrating a game apparatus embodying the principles of the present invention;

FIGURE 2 is a front elevational view, partially in section, of a portion of the game apparatus illustrated in FIG. 1;

FIGURE 3 is a plan view of the game apparatus illustrated in FIG. 1;

FIGURE 4 is an enlarged fragmentary elevational view, partially in section, of the chute members of the game apparatus of the present invention;

FIGURE 5 is a plan view of the chute members illustrated in FIG. 4;

FIGURE 6 is an elevational view of the chute member illustrated in FIG. 4 in its preassembled condition;

FIGURE 7 is a front elevational view of the pocket portion of the chute member illustrated in FIG. 4 in its preassembled condition;

FIGURE 8 is a perspective view illustrating another embodiment of the present invention;

FIGURE 9 is a side elevational view, partially in section, of the game apparatus illustrated in FIG. 8;

FIGURE 10 is a plan view of the base portion of the game apparatus of FIG. 8;

FIGURE 11 is a perspective view of a chute member adapted for use with the embodiments of the invention illustrated in FIG. 8; and

FIGURE 12 is a front elevational view of the chute member of FIG. 11, in its preassembled condition.

In the embodiment of the invention illustrated in the drawing, the numeral 11 designates generally a target or ball-receiving receptacle having a base 12 in which a plurality of chute members 13 are mounted.

Base 12 comprises a series of side panels 14, 15, 16 and 17 which define an open top 12a. In order to align the bottom ends of the chutes 13 along a single plane, an inner platform 18 is provided and is positioned at about

2

half way between the top and bottom ends of the base 12. Thus, the relative heights of the chutes will be unaffected by the regularity of the surface upon which the base 12 is set. A series of intersecting partitions 19 serve to define a plurality of compartments 20 which are sized to be slightly larger than the individual chutes so that the chutes can be readily removed therefrom. The receptacle 11 can be composed of any suitably rigid material such as, for example, a heavy paper cardboard. In particular, a wax-impregnated corrugated board has been advantageously employed.

Chutes 13 are removably mounted in parallel alignment in the compartments 20 and are sized to loosely receive a rubber ball which is to be thrown or bounced therein. For example, square chutes with sides of four inches each have been found to work particularly well with rubber balls of two and one-half inches in diameter. Recovery of balls which successfully travel into one of the chutes is facilitated by the provision of pocket-forming members 21 in the chutes 13. As shown in FIGS. 4 and 7, these members each include a base 22, sized to be slightly smaller than the interior cross section of the chute 13, and side-flap portions 23 which are adapted to be secured to the inner walls of the chute by means of paper clips or a suitable adhesive. While the actual pocket depth will be dependent upon the ball size, it should be noted that it is desirable to make the pockets sufficiently deep so that the balls will not bounce out of the chute once they land therein. For example, pocket depths of four inches have been found to be adequate for use with rubber balls of two and one-half inches in diameter.

The chutes 13 and their pocket-forming portions 21 are illustrated in their unfolded or preassembled condition in FIGS. 6 and 7. As is shown therein, the chute housing 35 includes a single sheet member 13a on which five longitudinal panels a, b, c, d, and e are marked. In assembling the chute 13, member 13a is folded along the lines 13b and panel a is secured to panel e by means of a paper clip or adhesive. In practice, it has been found that folding panel e over panel a and sizing panel a so that it is somewhat smaller than panel e produces an attractive and sturdy chute construction. In order to effect good fitting of the pocket-forming member 21 within the chute 13, flaps 23 can be sized so that they are slightly shorter than the respective sides to which they are secured (FIG. 7). Thus, when the flaps 23 are secured to the interiors of the panels a, b, c, and d, the end portions thereof will easily fit within the interior of the chute 13.

While the number of chutes and the respective heights of each is a matter of choice, it has been found that a target including nine chutes of varying heights between nine and twenty-four inches produces a relatively stable construction which is not easily tipped over by reason of improperly aimed balls.

The actual game rules can, of course, be varied depending upon the skills of the players, however, they will basically involve either throwing or bouncing a ball into the chutes and determining a score by reason of the point value associated with the particular chute in which the ball has landed.

It will be appreciated that since each of the chutes is of the same cross-sectional construction, their arrangement can be varied. Thus, if it is desired to increase the difficulty of scoring, the taller chutes can be positioned at the forward end of the base 12 and the shorter chutes set up at the rear.

Another variation of the present invention is illustrated in FIGS. 8-12, and includes a compartmented base, similar to base 11 of FIG. 1, in which one or more chutes is inserted. Each of the chute sides has two sets of numerals marked thereon, one set designating the point value for bouncing a ball in the chute, and the other representing

the point value for bouncing a ball into the adjacent open compartments of the base. For example, in the illustrated embodiment (FIGS. 8-10), base 30 having nine compartments (32-40), is provided with a chute 31 supported within compartment 36. Chute 31 has an open top 31a, sized to receive a ball to be thrown or bounced therein and is fitted with a pocket-forming member 41 for facilitating recovery of balls which have landed in the chute.

As is shown in FIGURE 9, pocket-forming member 41 is positioned sufficiently below open end 31a so that ball 41 will not bounce out of the chute once it has successfully landed therein. Ball recovery is facilitated by the removability of chute 31. For example, in recovering a ball from chute 31, a player need merely lift the chute from the base 30 and turn it upside down. In this regard, it should be noted that pocket depth is not limited by the ease of ball recovery.

As is shown, each of the sides of chute 31 has a number "4" marked at the uppermost portion thereof, denoting the point value for getting the ball in the chute. The lowermost visible portion of each of the chute sides is provided with the numeral "2," which represents the point value for getting the ball into the adjacent open compartments (33, 35, 37 and 39). Compartments 32, 34, 38 and 40 have no point value.

When chute 31 is positioned in compartment 36, a total of five scoring pockets are provided. This number is reduced to four when the chute is positioned in compartments 33, 35, 37, or 39, and to three by moving it to any one of the corner compartments 32, 34, 38, or 40. In addition, more chutes can be added to provide a multitude of variations for the players.

An interesting variation on the embodiment illustrated in FIGS. 8-10 involves using different values for each of the open compartments surrounding the chute. For example, in FIG. 11, a chute 42 is shown having the numeral "20" as the chute value and the numerals "2," "4," "6" and "8" as the point values for the respective compartments adjacent each of the respective chute sides. These numbers are, of course, positioned so that they are visible when the chute is properly inserted in any of the base compartments.

One method for constructing the chute 42, without the use of paper clips or adhesive, involves cutting and marking a piece of heavy paper or cardboard in accordance with the manner illustrated in FIG. 12. As is shown therein, the sheet is divided into five longitudinal panels (f through j) which are separated by the lines 42b along which the sheet is to be folded. At one end of the panels, corresponding end tabs f' through j' are provided. Each of these tabs is adapted to be folded along the lateral lines 42c and 42d so that the portion on each of the tabs between lines 42c and 42d will lie flush with the back face of the respective panel to which it is connected. In forming chute member 42, the sheet is first folded along the lines 42b so that panel j overlies panel f. The individual tabs are then folded along the lines 42c and 42d, to form pocket portion 43, and extension 44 on tab h' is inserted in the hole 45 of panel f. Thus, a rectangular chute 42 can be easily assembled, and, if desired, can be easily dismantled by following the reverse process. This construction can be advantageously incorporated in the game apparatus of the present invention, so that the ultimate consumer can easily assemble the game for himself, thereby substantially reducing both production and shipping costs.

While, in the foregoing specification, the invention has been described in considerable detail for purposes of illustration, it will be understood by those skilled in the art that many of the details may be varied without departing from the spirit and scope thereof.

I claim:

1. A game apparatus, comprising, in combination, a base, and a plurality of longitudinal chute members of significantly varying heights removably mounted therein, said base having an open top and a plurality of compartments dimensioned to engage with the sides of said chutes for supporting said chutes in an upright position, said chutes having an open top and being sized to receive a ball thrown therein, said chutes being provided with an inner platform transversely disposed with respect to the longitudinal axis thereof for supporting a ball when thrown therein.

2. The combination defined in claim 1 wherein said base is provided with an inner platform which is adapted to supportingly receive the bottom ends of said chutes for aligning said bottom ends along a single plane.

3. A game apparatus, comprising, in combination, a box having an open end and a plurality of longitudinal chute members of significantly varying heights removably mounted therein and extending through said open end, said chutes each having an open top and being sized to receive a ball therein, said box including a series of intersecting panel members providing a plurality of compartments which are dimensioned to engagingly receive said chutes for supporting said chutes in an upright position, said chutes being provided with an inner platform member transversely disposed with respect to the longitudinal axis thereof for supporting a ball which has been thrown therein.

4. The combination defined in claim 3 wherein said box is provided with an inner platform which is adapted to receive the bottom ends of said chutes for aligning said bottom ends along a single plane.

5. A game apparatus, comprising, in combination, a ball, a base, and a plurality of longitudinal chute members of widely varying heights removably mounted in said base, said base having an open top and a plurality of compartments dimensioned to engage with the sides of said chutes for supporting said chutes in upright position, said chutes having open tops and being sized to selectively and separately receive said ball when thrown therein, said chute members including ones varying in height by at least 9 to 24 inches.
